UNITED STATES PATENT OFFICE.

THEODORE G. SCHMEISER, OF SAN FRANCISCO, CALIFORNIA.

GROUSER.

Application filed March 30, 1927. Serial No. 179,537.

The present invention relates to improvements in grousers and has particular reference to grousers adapted to be used in connection with the traction wheels of a tractor.

5 My invention has particular reference to a grouser intended to be used on the wheel of the Fordson tractor which presents on the surface thereof a series of diagonally arranged holes for receiving bolts for fastening the grousers thereto.

10 In the present invention it is proposed to present a grouser which is particularly strong in construction in the points most subject to wear, and for this purpose I propose to provide a wedge-shaped grouser having a large portion of the material crowded into the tip while being hollow at the base and the intermediate portion, so that the tip substantially balances the base in weight. It 15 is further proposed to provide certain improvements in the means for fastening the grouser to the traction wheel, the principal novel feature being that the flanges adapted to receive fastening bolts are arranged within 20 the outlines of the grouser and do not project therefrom so that they may not be knocked off. Further objects and advantages of my invention will appear as the specification proceeds.

25 The preferred form of my invention is illustrated in the accompanying drawing, in which:

Figure 1 shows an end view of my grouser as attached to the rim of a traction wheel;

30 Figure 2 shows a front view thereof;

Figure 3 shows a vertical section taken along line 3—3 of Figure 2;

Figure 4 shows a bottom plan view of my grouser; and

35 Figure 5 shows a top plan view of the same.

While I have shown only the preferred form of the invention, I wish to have it understood that various changes or modifications 40 may be made within the scope of the claims hereto attached without departing from the spirit of the invention.

45 In its preferred form, my grouser 1 is preferably a wedge-shaped pyramid in its general outlines, so as to present a base 2, surface elements 3 and a tip 4, the base being slightly curved to correspond to the curvature of the rim 6 of a traction wheel. The side surface elements or working faces 3 are formed to present a compound curve in the 50 manner of a sinuous curve, the convex com-

ponent of the curve being at the apex portion whereby the thickness of the metal is increased toward the tip and the concave component of the curve extends toward the base of the grouser to provide better and quicker clearance for the grouser.

55 The grouser is made hollow as shown at 7 and presents inner walls running substantially parallel to the outer walls throughout the base and intermediate portion of the grouser, while the tip portion is made solid as shown in the drawing;—the solid portion including substantially one-third to two-fifths of the height of the grouser. The 60 inner walls of the grouser meet along a curved line 8 spaced from the tip in the manner aforesaid.

65 Diagonally opposed corners of the grouser are recessed as shown at 9 to provide seats 75 11 for the heads 12 of bolts 13 extending through perforations in the said seats and registering perforations 14 in the wheel rim so as to allow the grouser to be fastened to the wheel rim by means of nuts 16 threaded 80 on the inner ends of the bolts, spring washers 17 being preferably interposed between the nuts and the rim. It will be noted that the recessing of the corners of the grouser allows the seats 11 to be substantially confined within the outlines of the grouser so that they do not project from the grouser and do not offer any point of attack to a force attempting to break them away from the grouser.

75 90 It will further be noted that the walls of the recesses 9 are arranged at right angles as shown particularly well in Figures 4 and 5, so that the walls serve as a stop for the bolt head, and prevent the latter from turning.

95 Grousers of this character are reversible, and may be turned about after one face is worn down. They are not interchangeable from one wheel to another, since in the 100 standard arrangement of traction wheels the series of holes for fastening the grouser are not arranged parallel in a pair of wheels, but along intersecting lines.

105 It will be understood that grousers of this character are less subject to wear than grousers with straight surface elements, since the bulk of the material is crowded into the tip portion, and my grousers may be used for a long time before the curvature wears out, 110 while furthermore the period of usefulness may be doubled by reversing the grousers.

The fact that the seats are arranged within the compass of the wedge prevents the same from being easily damaged.

I claim:

- 5 1. A grouser of the character described, comprising a pyramidal wedge shape block, the working faces of said wedge defining a compound curve, the convex component thereof disposed at the apex portion of the 10 wedge to provide greater strength, the concave component at the base portion of the wedge providing extra clearance.
- 10 2. A wedge shaped grouser of the character described having opposite edges re-

cessed to present seats for the heads of bolts 15 extending through perforations in said seats, said recesses being substantially confined in the outlines of the base of the wedge portion of the grouser.

3. A wedge shaped grouser of the character described having diagonally opposite edges recessed to present seats for the heads 20 of bolts extending through perforations in said seats, the walls of the recesses being arranged at an angle to prevent said heads from turning, said recesses lying within the 25 confines of the base of the wedge.

THEODORE G. SCHMEISER.
